[57] CLAIM

The ornamental design for a fishing line retainer, as shown and described.

DESCRIPTION

FIG. 1 is a perspective view of a fishing line retainer showing my new design;

FIG. 2 is a top plan view of the fishing line retainer, the reverse or bottom view being similar in appearance;

FIG. 3 is a side view of the fishing line retainer;

FIG. 4 is a side view of the fishing line retainer, the side illustrated being opposite that shown in FIG. 3;

FIG. 5 is an end view of the fishing line retainer as seen from left to right in FIG. 3; and

FIG. 6 is an end view of the fishing line retainer as seen from right to left in FIG. 3.
